by *Alexander S. Lantz*
His Attorney.

UNITED STATES PATENT OFFICE.

OLIVER C. TRAVER, OF SCHENECTADY, NEW YORK, ASSIGNOR TO GENERAL ELECTRIC COMPANY, A CORPORATION OF NEW YORK.

CIRCUIT-CONTROLLING DEVICE.

Application filed January 12, 1924. Serial No. 685,936.

My invention relates to improvements in circuit controlling devices and more particularly to circuit controlling devices for controlling a circuit a plurality of times in succession at predetermined intervals.

Electric line circuits are usually provided with suitable circuit breakers arranged to be opened on the occurrence of an abnormal circuit condition. Inasmuch as continuity of service may thus be interrupted, it is often the practice to reclose a circuit breaker automatically one or more times in succession at intervals so that, if the abnormal condition has disappeared, service will be promptly restored. In order, however, that the line and circuit breaker may not be subjected to unnecessary shocks, it is desirable to limit the number of times the circuit breaker may be reclosed so that if the abnormal condition prevails longer than a predetermined time, the circuit breaker will remain open. Moreover, in order to require the minimum personal attention, it is desirable to have the circuit breaker controlling device self-restoring when the circuit breaker is reclosed any number of times up to and including the predetermined number within the predetermined time and remains closed due to the disappearance of the abnormal condition. Furthermore, it is often desirable to have the time intervals such that the successive closures occur at increasing intervals, as by so doing it is possible, without impressing too frequent shocks on the line and circuit breaker, to test the permanency of the abnormal condition so as to restore service promptly upon the disappearance thereof.

An object of my invention is to provide an improved circuit controlling device which is operative automatically to control a circuit a plurality of times in succession at readily variable predetermined intervals and within a predetermined time at the expiration of which further operation may be suspended and which is particularly adapted for controlling the reclosing of a circuit breaker under the conditions hereinbefore set forth, although its application is not so limited.

My invention will be better understood from the following description taken in connection with the accompanying drawing and its scope will be pointed out in the appended claims.

The single figure of the accompanying drawing illustrates in perspective an em-

bodiment of my invention and shows diagrammatically an application thereof in a reclosing circuit breaker control system.

In general, my invention comprises relatively movable cooperating contacts 1 and 2, and means comprising a plurality of spaced actuating members 3, 4 and 5 movable simultaneously in one direction by any suitable power operated means such as a motor 6 successively to actuate the contacts 1 and 2. For controlling the movement of the members 3, 4, and 5, I provide means such as an electromagnet 7 and an armature 8 arranged in the normal position of the armature to hold the members 3, 4 and 5 in a predetermined position, as illustrated in the drawing, and in another position of the armature to permit the motor 6 to move the members 3, 4 and 5 from the predetermined position in one direction, clockwise as illustrated in the drawing, so as to actuate the contacts 1 and 2 at intervals dependent on the spacing of the members 3, 4 and 5, and arranged to prevent further movement of the members until the armature is returned to the normal position.

The actuating members 3, 4 and 5 may be mounted as radially disposed arms of a suitably mounted rotatable member such as a shaft 9 to which is secured a gear 10 of a reducing gear train 11 arranged to be driven by the motor 6. For varying the spacing of the arms 3, 4 and 5 so as to obtain the desired intervals between actuation of the contacts 1 and 2, the arms are adjustably positioned on the shaft 9 by any suitable clamping means such as a nut 12 and washers 13 and 14, and the gear 10 is preferably suitably graduated to indicate the correct positioning of the arms for the desired time intervals. In order that the balance of the load on the shaft 9 may be maintained substantially constant irrespective of the positioning of the arms 3, 4 and 5, they may be provided with counter-balancing portions 3', 4' and 5' respectively.

For controlling the movement of the arms 3, 4 and 5 by the motor 6, which may be continuously energized, the normal position of the armature 8 may be the unattracted position to which the armature 8 is biased by any suitable means such as a spring 15. In this position the armature 8 is arranged to be engaged by any suitable means such as an engaging member 16 secured to the shaft 8 whereby to hold the arms 3, 4 and 5 in one

position. When the electromagnet 7 is energized and the armature 8 thereby moved to another or attracted position, the engaging member 16 is released and the arms 3, 4 and 5 are free to rotate under the torque exerted by the motor 6 at a rate dependent on the speed thereof. Therefore, for uniformity in time delay action, the motor 6 is preferably a substantially constant speed motor.

10 As the arms 3, 4 and 5 are rotated, each actuates the contacts 1 and 2 once, at intervals dependent on the spacing of the arms. For reclosing circuit breaker operation, these intervals preferably progressively increase the 15 first interval being relatively short, the second interval relatively long and the third interval still longer. My invention, however, is not limited to this number or order of time intervals, as it is obvious that the number of arms and the spacing thereof may be varied to provide any desired number and order of intervals.

In order that the actuation of the contacts 1 and 2 may be effected positively with 25 a minimum load on the motor, they are mounted on pivots 17 and 18 respectively and arranged to provide a hammer blow action on closure. For this purpose, the free end of contact 1 is mounted for lost motion and supported by any suitable means such as a rest 19 and in turn supports the free end of contact 2 by any suitable means such as a flange 20, so that, as one of the arms 3, 4 and 5 moves towards the contacts, it first engages and moves contacts 1 and 2 simultaneously upward and subsequently releases contact 1 and engages and moves contact 2 towards contact 1 which is now falling towards contact 2, thereby insuring a good contact closure.

For further controlling the movement of the arms 3, 4 and 5, the armature 8 is provided with a stop 21, which, when the armature is in the attracted position, is arranged 40 to be engaged by an engaging member 22, which may be angularly displaced relatively to the engaging member 16 in advance thereof, considering the direction of motion, so as to permit substantially one revolution of 50 the shaft 9 before the arms 3, 4 and 5 are brought to a stop after actuating the contacts 1 and 2. The stop 21 may be such that upon deenergization of the electromagnet 7 the armature 8 will, under the bias of spring 55 15, be returned to the unattracted position whereupon the stop 21 will be released from the engaging arm 22 and permit the motor 6 to rotate the shaft 9 clockwise as shown in the drawing until the engaging arm 16 60 abuts the end of the armature 8. I may further provide the armature 8 with means such as a flange or collar 23 such that, if the armature is in the attracted position when the engaging member 22 abuts the stop 21, 65 the armature 8 cannot return to the normal

or unattracted position when the electromagnet 7 is deenergized. In this way automatic operation of the circuit controlling device may be suspended, even though the electromagnet 7 is deenergized.

In order to reset the device for automatic operation, I provide means adapted to be operated to free the engaging member 22 from the flange 23 whereupon the armature 8 will be returned to its unattracted position 70 by the spring 15, if the electromagnet 7 is not energized. This means may comprise a lug 24 mounted on the gear 10 in such a position as to be engageable by a suitable operating member such as a finger lever 25 80 when the engaging arm 22 bears against the stop 21. Under these conditions, clockwise rotation of the lever 25 will turn the gear 10 and shaft 9 counter-clockwise sufficiently to free the engaging arm 22 from 85 the flange 23. To prevent over travel of the gear 10 and parts associated therewith upon actuation of the lever 25, I may provide the gear with a stop lug 26 arranged to engage the lever 25 after a predetermined 90 counter-clockwise movement of the gear 10.

Within the scope of my invention, the type of motor used is immaterial, although I preferably use an electric motor having a substantially constant speed characteristic 95 as by so doing it is possible to obtain greater uniformity in timing operation. The motor 6 illustrated is of the shaded pole induction disk type, as I have found that such a motor will serve the purpose very 100 well and can be designed to accelerate very quickly and maintain a substantially constant speed even with considerable variation in voltage. In order to avoid shocks to the mechanism by the somewhat abrupt stopping and starting thereof and when the lever 25 is operated to reverse the direction of movement of the gear 10 and its associated parts, I preferably provide a resilient connection between the shaft 27 of the motor 6 110 and the gear train 11. This connection may comprise a spring 28 secured to the motor shaft 27 and to suitable means such as a toothed wheel 29 secured to the first gear 30 of the gear train 11, one end of the motor 115 shaft 27 being journaled in the shaft 31 on which the toothed wheel 29 and the gear 30 are mounted. The initial torsion in the spring 28 may be varied by changing the point of engagement of the spring 28 with 120 the toothed wheel 29.

In order more clearly to set forth the operation of the illustrated embodiment of my invention, I have shown diagrammatically an application thereof for reclosing a 125 latched-in type of circuit breaker 32 which is arranged to control a line circuit 33 connected to a main bus 34 and to be opened in response to a predetermined abnormal condition, such as excess current, by an 130

over-current relay 35. The circuit breaker 32 may be provided with any suitable closing means such as a closing coil 36, the circuit of which is normally open and arranged 5 to be closed on actuation of the contacts 1 and 2. These contacts are shown directly in the circuit of the closing coil 36 for the sake of simplicity, although the usual practice is to have the relatively light contacts 10 1 and 2 control a relay having contacts of sufficient current carrying capacity to carry the relatively large current demand of the closing coil.

Any suitable source such as an auxiliary 15 bus 37 energized from the main bus 34 through a potential transformer 38 may be used to energize the motor 6, the electromagnet 7, the closing coil 36 and a manually controlled trip or opening coil 39. The 20 circuit breaker 32 is provided with an auxiliary switch 40 arranged to control the circuit of the electromagnet 7 so that the circuit thereof is open when the circuit breaker 32 is closed and vice-versa.

25 Assuming that the parts are positioned as shown in the drawing, and that something happens on the circuit 33 to cause the actuation of the relay 35, the circuit breaker 32 will be tripped and move to circuit open 30 position. The circuit of the electromagnet 7 is thereby completed by the auxiliary switch 40 and the end of the armature 8 moved away from the engaging member 16. The motor 6 being energized continuously

35 from the auxiliary bus 37 at once moves the arms 3, 4 and 5 clockwise. After a relatively short interval, contacts 1 and 2 are actuated by arm 3 and the circuit of the closing coil 36 completed thereby causing 40 the circuit breaker 32 to be closed. Upon the closing of the circuit breaker, the electromagnet 7 is again deenergized and the armature 8 moves to the unattracted position under the bias of spring 15. If the 45 circuit breaker 32 remains closed due to the disappearance of the abnormal condition, the arms 3, 4 and 5 will continue to be rotated until the engaging member 16 makes one revolution and is held by the armature 8. If, however, the circuit breaker 50 32 opens a second time, it will be closed again after a longer interval when contacts 1 and 2 are actuated by arm 4. If the circuit remains closed due to the disappearance

55 of the abnormal condition, the arms 3, 4 and 5 will continue to rotate until stopped by the engagement of the engaging arm 16 with the armature 8. If, however, the circuit opens the third time, it will again be closed after a still longer interval when arm 5 actuates contacts 1 and 2, and if it stays closed due to the disappearance of the abnormal condition, rotation of the arms 3, 4 and 5 will be stopped when the engaging member 16 meets armature 8.

Assuming that the circuit breaker 32 opens the fourth time before the engaging arm 22 has moved past the armature 8, then stop 21 will hold the engaging member 22 since the armature 8 is in the attracted position. The 70 circuit controlling device is now locked out and must be reset. This may be done with the circuit breaker 32 open by opening a switch 41 in the circuit of the electromagnet 7 and actuating the lever 25 so as to 75 move the engaging member 22 counter-clockwise sufficiently to clear the flange 23. If it is desired to trip the circuit breaker 32 without putting the circuit controlling device into operation, the switch 41 may be 80 arranged so that in order to close the circuit of the opening coil 39 it must first be moved to open the circuit of the electromagnet 7, then when the circuit breaker is opened, the auxiliary switch 40 does not complete 85 the circuit of the electromagnet 7. The auxiliary switch 40 may also be arranged to control contacts in the circuit of the opening coil 39 so that the circuit breaker 32 will be immediately tripped open unless the switch 41 is closed on the circuit of the electromagnet 7. In this way an operator cannot leave the circuit controlling device inoperative. The circuit of the closing coil 36 may also be arranged for manual control by a switch 42 so that the circuit breaker can be closed independently of the circuit controlling device.

It is therefore obvious that with circuit controlling devices embodying my invention, 100 a circuit breaker can be reclosed one or more times at predetermined intervals which may be as desired and, if the circuit breaker remains closed any one of these times, the device remains operative to control the circuit breaker. If, however, the circuit breaker opens immediately after the third closure, it will be locked out, as operation of the device is suspended and the device must be reset before again acting automatically 105 to reclose the circuit breaker.

While I have shown and described only one embodiment of my invention, I do not wish to be limited to the exact arrangement shown and described, but seek to cover in 110 the appended claims all those modifications that fall within the true spirit and scope of my invention.

What I claim as new and desire to secure by Letters Patent of the United States, 115 is:

1. In a device of the class described, two relatively movable cooperating contacts, means comprising a plurality of spaced actuating members movable simultaneously in one direction successively to actuate said contacts, power operated means for moving said members in said direction, and means for controlling the movement of said members by said power operated means 125 130

comprising an electromagnet and armature arranged in the normal position of the armature to hold said members in a predetermined position and in another position of the armature to permit said power operated means to move said members from said position to actuate said contacts at intervals dependent on the spacing of said members, said movement controlling means being arranged to prevent full movement of said members to said predetermined position until the armature is returned to normal position.

2. In a device of the class described, relatively movable cooperating contacts, means comprising a plurality of adjustably positioned members rotatable simultaneously in one direction successively to actuate said contacts, means comprising a motor adapted continuously to exert a torque for moving said members in said direction, and means for controlling the movement of said members by said motor comprising an electromagnet and armature arranged in the normal position of the armature to hold said members in a predetermined position and in another position of the armature to permit said motor to move said members from said position a predetermined amount whereby said contacts are actuated at intervals dependent on the positioning of said members.

3. In a device of the class described, relatively movable cooperating contacts, a rotatable member comprising a plurality of angularly spaced substantially coplanar arms arranged upon rotation of said member in one direction successively to actuate said contacts, means comprising a motor for turning said member in said direction, and means for holding said member in a plurality of positions comprising an electromagnet arranged when deenergized to hold said member in one position and when energized to permit said motor to turn said member from said position whereby said contacts are actuated by said arms at intervals dependent on the spacing thereof, said electromagnet being arranged to hold said member in another position until deenergized.

4. In a device of the class described, relatively movable cooperating contacts, a rotatable member comprising a plurality of spaced arms arranged upon rotation of said member in one direction successively to actuate said contacts, means comprising a motor for turning said member in said direction, and means for controlling the movement of said member comprising an electromagnet provided with a movable armature and means carried by said member and arranged to engage said armature in one position thereof whereby said member is held in a predetermined position and to permit a predetermined movement of said member in said direction when said armature is moved

to another position whereby said contacts are actuated once by each of said arms at intervals dependent on the spacing thereof.

5. In a device of the class described, relatively movable cooperating contacts, a rotatable member comprising a plurality of spaced arms arranged upon rotation of said member in one direction successively to actuate said contacts, means comprising a motor for turning said member in said direction, and means for controlling the movement of said member comprising an electromagnet provided with a movable armature and means carried by said member and arranged to engage said armature in one position thereof whereby said member is held in a predetermined position and to be released upon movement of said armature to another position thereby to permit movement of said member in said direction whereby said contacts are actuated once by each of said arms at intervals dependent on the spacing thereof, and subsequently to engage said armature and hold said member in another position whereby further movement of said member is prevented.

6. In a device of the class described, relatively movable cooperating contacts, a rotatable member comprising a plurality of spaced arms arranged upon rotation of said member in one direction successively to actuate said contacts, means comprising a motor for turning said member in said direction, and means for controlling the movement of said member comprising an electromagnet having an armature biased for movement to the unattracted position, and a plurality of spaced engaging members carried by said rotatable member, one of said engaging members being arranged to engage said armature in the unattracted position whereby said rotatable member is held in one position when said electromagnet is deenergized, and to be released upon movement of said armature to the attracted position thereby to permit movement of said rotatable member in said direction whereby said contacts are actuated once by each of said arms at intervals dependent on the spacing thereof and another of said engaging members being arranged subsequently to engage said armature only when in the attracted position whereby further movement of said rotatable member is prevented.

7. In a device of the class described, relatively movable cooperating contacts, a rotatable member comprising a plurality of spaced arms arranged upon rotation of said member to actuate said contacts, means comprising a substantially constant speed motor for turning said member in said direction, and means for controlling the movement of said member comprising an electromagnet provided with a movable armature, means carried by said rotatable member and ar-

ranged to engage said armature when in the normal position whereby said rotatable member is held in a predetermined position and to be released upon movement of said armature to another position thereby to permit movement of said rotatable member in said direction whereby said contacts are actuated once by each of said arms at intervals dependent on the spacing thereof and subsequently to engage said armature only when in said other position whereby further movement of said rotatable member is prevented, and means associated with said armature and arranged to engage said engaging means whereby to prevent said armature from returning to normal position.

8. In a device of the class described, relatively movable cooperating contacts, a rotatable member comprising a plurality of spaced arms arranged upon rotation of said member to actuate said contacts, means comprising a substantially constant speed motor for turning said member in said direction, and means for controlling the movement of said member comprising an electromagnet provided with a movable armature, means carried by said rotatable member, and arranged to engage said armature when in the normal position whereby said rotatable member is held in a predetermined position, and to be released upon movement of said armature to another position thereby to permit movement of said rotatable member in said direction whereby said contacts are actuated once by each of said arms at intervals dependent on the spacing thereof and subsequently to engage said armature only when in said other position whereby further movement of said rotatable member is prevented, means associated with said armature and arranged to engage said engaging means whereby to prevent said armature from returning to normal position, and means adapted to be operated to release said engaging means from said armature whereby said armature is free to move to normal position.

9. In a device of the class described, relatively movable cooperating contacts, a rotatable member comprising a plurality of adjustably positioned and counterbalanced

arms arranged upon rotation of the member in one direction successively to actuate said contacts, means comprising a motor for turning said member in said direction, and means for controlling the movement of said member comprising an electromagnet provided with a movable armature and means carried by said member and arranged to engage said armature in one position thereof whereby said member is held in a predetermined position and to permit a predetermined movement of said member in said direction when said armature is moved to another position whereby said contacts are actuated successively by said arms at intervals dependent on the positioning thereof.

10. In combination with a circuit breaker, means adapted to effect the closing of the circuit breaker a plurality of times in succession at predetermined intervals comprising a movable member, power operated means tending to actuate said member and means for holding said member in one position arranged to be released by the opening of the circuit breaker and to hold the member in another position when the circuit breaker is open after the member has been moved sufficiently to effect the closing of the circuit breaker a predetermined number of times.

11. In combination with a circuit breaker, means adapted to effect the closing of the circuit breaker a plurality of times in succession at predetermined intervals comprising a rotatable member, a motor arranged continuously to exert a torque on said member, and means comprising an electromagnet controlled by said circuit breaker and having an armature arranged in normal position to hold said member in a predetermined position when the circuit breaker is closed and to be actuated to another position to release the member when the circuit breaker opens, said armature being arranged to prevent full movement of said member to said predetermined position until the armature is returned to normal position.

In witness whereof, I have hereunto set my hand this 10th day of January, 1924.

OLIVER C. TRAVER.
